UNITED STATES PATENT OFFICE.

JOHN SIMON FLUOR, OF SANTA ANA, CALIFORNIA.

APPARATUS AND METHOD OF CONSTRUCTING WALLS.

1,368,131.

Specification of Letters Patent.

Patented Feb. 8, 1921.

Application filed October 16, 1919. Serial No. 331,224.

To all whom it may concern:

Be it known that I, JOHN SIMON FLUOR, a citizen of the United States, residing at Santa Ana, in the county of Orange and

5 State of California, have invented new and useful Improvements in Apparatus and Methods of Constructing Walls, of which the following is a specification.

This invention relates to wall, floor, panel 10 or other monolithic cement construction and has for its object to provide an improved method for the simplification of the construction of monolithic walls of cement, and also to provide a monolithic wall or partition structure that is at once constructible 15 at comparatively small expense and which will be rigid and that can be constructed in successive stages as its area may require, and the invention consists of the method and 20 the wall apparatus as will be described more particularly hereinafter.

Figure 1 is a perspective view of monolithic standards as erected in the practice of the method of building a wall.

25 Fig. 2 is a central longitudinal section through one of the monolithic standards showing the reinforcement embedded therein.

Fig. 3 is a sectional view of a modified form of the standard.

30 Fig. 4 is a detail sectional view illustrating the foundation on which the base or foot of a standard is erected.

Fig. 5 is a perspective view of a wall in the course of construction according to the 35 method herein set forth.

Fig. 6 is a detail transverse section on a vertical plane through a portion of the wall and the mold apparatus associated therewith.

40 According to my method for constructing a monolithic cement panel or wall I first produce a longitudinal monolithic member hereinafter termed the standard, although it is to be understood that such term is not 45 to be interpreted as limiting the character of the use of the member. This standard, in its embodiment shown in Figs. 1 and 2, comprises substantially parallel spaced parts 2-2 of suitable transverse sectional area 50 and proportions in which, during the process of their manufacture, there are embedded suitable reinforcing means as rods 3, Fig. 2; these parallel side parts being transversely integrally connected as by ties 4 55 spaced at suitable intervals along the length

of the standard and each of suitable thickness and length according to the purpose for which the standard may be utilized; and when the standards are to serve as columns, in the formation of a vertical wall, the foot 60 end of the column or standard may be provided with enlargements or toes 5-5 to facilitate the embedding and supporting thereof upon a suitable foundation which is shown in Fig. 4 at 6 wherein the foundation consists of cement which may be grouted in around the bases of the columns, a series of which may be arranged in suitable relation as in a vertical plane shown in Fig. 1. In addition to the longitudinally extending reinforcing rods or means 3 other transverse reinforcing members 3^a may be utilized to increase the strength and rigidity 70 of the standards.

In Fig. 3 there is illustrated a modified 75 form of standard or post construction in which the side bars or elements 2' are spaced from each other a suitable distance, and instead of being integrally connected as by the ties 4 of cement are connected only by transverse reinforcing or connecting irons or rods 4'.

With a wall of given thickness, height and length to be erected, a series of the columns or standards is emplaced in the foundation 85 6 and reinforcing material as the vertical and horizontal rods 8 and 9 are fabricated on the erected columns, the horizontal rods, for instance, being supported upon the upper horizontal edges of the transverse ties 90 4 or rods 4', as the case may be.

Any suitable false work to temporarily support the columns or standards may be employed when they are set upright, and these temporary braces are indicated at B 95 as pieces of timber suitably disposed and anchored or connected to each of the columns as by bolts C which may be passed through the interstices along the standards and mounted in cross blocks D. Along the 100 upper ends of the erected standards there may be run a temporary tie in the form of pieces of timber E which may be nailed to cap blocks F wired or otherwise removably connected on the upper ends of the columns 105 as at G.

Having thus erected and braced a series of columns or standards to be embedded in a finished concrete wall there is then laid along the outer faces of the standards S a 110

series of sections of mold forming means, in the present case each of the sections being illustrated as of a length to extend from one standard S to the other and overlap the same; the series of sections 10 forming the mold having their adjacent ends brought into close juxtaposition or abutted as shown in Fig. 5.

In the first step of casting the wall the 10 mold sections 10 are rested upon the top surface of the foundation 6 and secured vertically against the outer side faces of the standards S as by wires 11 and 12 which can be run through apertures provided therefor 15 in the mold boards or sections and twisted on the opposite sides as at 13. Each of the mold board sections is shown as comprising a plurality of planks or other sheet material forming a plane inside face and they 20 are reinforced and braced along the outside face by upright cleats 14. To further stiffen up the mold board sections longitudinal cleats or strips 15 can be laid against the outer faces of the upright cleats 14 and these 25 longitudinal strips can be braced by short strips or braces 16 secured thereto at their upper ends and to the sides of the lower portions of the cleats 14.

While the mold boards are applied to the 30 lowermost portion of the erected columns or standards S the space between the mold boards is filled with plastic cement which is suitably grouted or tamped to the desired degree of solidity, and when this first and 35 lowermost filling has hardened the fastening wires 11 and 12 are clipped to release the mold board sections 10—10 which may then be elevated a suitable distance or to such a degree that their lower edges will stand 40 slightly below the top surface of the first filling between the standards in which position they are secured by the wires 11 and 12 as shown in Fig. 6.

In order to support the weight of the 45 mold board sections 10 as they are successively vertically erected, any suitable temporary supporting means may be employed represented here as light strips 20 of wood or other material which may be jacked up 50 under the lower edge of the continuous mold forming series of panels 10. Obviously the space between the mold boards is again filled with cementitious material which is properly tamped, and after it has sufficiently 55 hardened the mold board apparatus is again detached and raised to a higher position and again jacked up by the strips 20 as above described.

This successive elevation of the mold 60 boards to different stages will be repeated until the entire wall has been erected to the top of the standards S after which the mold boards may be removed to be used again.

It will be understood that the temporary 65 bracing will be removed after the wall

forming cement has been inserted to a sufficient height to stabilize the upright standards S.

Obviously, instead of using wire ties 11 and 12, as shown in Fig. 6, any suitable 70 tie device might be used as, for instance, bolts or rods which it is not necessary to show.

Various changes may be made without departing from the spirit of my invention as 75 claimed.

I claim:

1. The method of building a monolithic cement wall or other structure, which consists of first preparing suitable standards of 80 cement for forming supports, erecting the said standards, emplacing and shoring the said standards; erecting molding apparatus against and along the opposite sides of the erected standards to form a mold chamber; 85 fabricating reinforcement upon and along the said erected standards; and filling the mold chamber with plastic cement mixture so as to permanently embed the said standards and form therewith a monolithic wall. 90

2. The method of building a monolithic cement wall or other structure, which consists of first preparing suitable standards of cement for forming supports; erecting the 95 said standards, emplacing and shoring the said standards and embedding their bases in plastic cementitious material; erecting molding apparatus against and along the opposite sides of the erected standards to form a mold chamber; fabricating reinforcement 100 upon and along the said erected standards; and filling the mold chamber with plastic cement mixture so as to permanently embed the said standards and form therewith a monolithic wall. 105

3. The method of building a monolithic cement wall or other structure, which consists of first preparing suitable standards of cement having spaced longitudinal side bars which are transversely connected for 110 forming supports; erecting the said standards, emplacing and shoring the said standards; erecting molding apparatus against and along the opposite sides of the erected standards to form a mold chamber; fabricating reinforcement upon and along the 115 said erected standards; and filling the mold chamber with plastic cement mixture so as to permanently embed the said standards and form therewith a monolithic wall. 120

4. The method of building a monolithic cement wall or other structure, which consists of first preparing suitable standards of cement having spaced longitudinal side bars which are transversely connected for 125 forming supports; erecting the said standards, emplacing and shoring the said standards; erecting molding apparatus against and along the opposite sides of the erected standards to form a mold chamber; fabri- 130

cating reinforcement upon and along the said erected standards; and filling the mold chamber with plastic cement mixture so as to permanently embed the said standards 5 and form therewith a monolithic wall, certain of the reinforcement being passed from standard to standard and between the side bars thereof.

5. The method of building a monolithic 10 cement wall or other structure, which consists of first preparing suitable standards of cement for forming supports; erecting the said standards, emplacing and shoring the said standards; erecting molding apparatus 15 against and along the opposite sides of the erected standards to form a mold chamber; fabricating reinforcement upon and along the said erected standards; and filling the mold chamber with plastic cement mixture 20 so as to permanently embed the said standards and form therewith a monolithic wall and in successive steps dismantling the mold apparatus and advancing it to successive stages following the setting of a previously 25 filled stage in which the set cement forms a bottom for the next upper stage.

6. The method of building a monolithic 30 cement wall or other structure, which consists of first preparing suitable standards of cement for forming supports; erecting the said standards, emplacing and shoring the said standards; erecting sectional molding apparatus against and along the opposite sides of the erected standards to form a mold 35 chamber; fabricating reinforcement upon and along the said erected standards; and filling the mold chamber with plastic cement mixture so as to permanently embed the said standards and form therewith a monolithic wall; and after the first filling 40 has set, individually raising each section to a successive stage at which the set cement forms a bottom and securing the respective sections in alinement to opposite sides of 45 the said standards by the wires passed across its wall; and later, clipping the wires to release the sections without removing the wires so that they reinforce the wall.

7. The method of building a monolithic 50 cement wall or other structure, which consists of first preparing suitable standards of cement for forming supports; erecting the said standards, emplacing and shoring the said standards; erecting molding appa-

ratus against and along the opposite sides 55 of the erected standards to form a mold chamber; fabricating reinforcement upon and along the said erected standards; filling the mold chamber with plastic cement mixture so as to permanently embed the said 60 standards and form therewith a monolithic wall, and jacking the mold apparatus by inserting along the lower edge thereof jack members which gage and determine the successive positions of the mold. 65

8. Means for constructing a wall or other monolithic structure of cement, comprising cement standards permanently erected in a series of given alinement and forming supports; means for temporarily shoring the 70 standards; and temporary mold apparatus secured to opposite sides of the series of standards to form therebetween mold space.

9. Means for constructing a wall or other monolithic structure of cement, comprising 75 cement standards permanently erected in a series of given alinement and forming supports; means for temporarily shoring the standards; and temporary mold apparatus secured to opposite sides of the series of 80 standards to form therebetween mold space, said apparatus adapted to be set at successive advanced stages along the permanent standards.

10. A monolithic cement wall including 85 standards, each standard comprising a reinforcement made of vertical rods and horizontal rods connecting said vertical rods, cement vertical members poured around said vertical rods, and cement cross members 90 poured around said horizontal rods and a cement body poured between said standards and through the spaces in said standards between the vertical members and the cross members thereof. 95

11. A monolithic cement wall including standards, each standard comprising a reinforcement, cement poured around said reinforcement forming spaced vertical members and spaced cross members connecting 100 said vertical members, and a cement body poured between said standards and through the spaces in said standards between said longitudinal members and said transverse members.

In testimony whereof I have signed my name to this specification.

J. SIMON FLUOR.
